DROP SEAT PAJAMA

Jack Bernstein, Brooklyn, N. Y.

Application June 3, 1937, Serial No. 146,146

5 Claims.

(Cl. 2-83)

This invention relates to wearing apparel and particularly to an improved drop seat pajama, the object being to provide a construction permitting the use of a drop seat without utilizing elastic members, buttons, or other similar fastening means.

Another object of the invention is to provide a drop seat pajama wherein there is provided a special belt arrangement for permitting the drop seat to be moved downwardly and upwardly without dislocating the belt structure.

A further object, more specifically, is to provide a pajama or similar garment with a drop seat and a belt formation with telescoping sections, the parts being so arranged that when the seat is lowered portions of one section will be pulled out of portions of the other section.

In the accompanying drawing:

Fig. 1 is a rear view of a pair of pajamas disclos-

ing an embodiment of the invention;

Fig. 2 is a sectional view on an enlarged scale through Fig. 5 on the line 2-2;

Fig. 3 is a sectional view on an enlarged scale through Fig. 5 on the line 3-3;

Fig. 4 is a sectional view on an enlarged scale through Fig. 5 on the line 4-4;

Fig. 5 is a fragmentary elevation showing part of the seat and approximately one-half of the belt structure associated therewith;

Fig. 6 is a sectional view through Fig. 5 approximately on the line 6-6;

Fig. 7 is a view similar to Fig. 5 but shown slightly in perspective and illustrating a modified form of the invention;

Fig. 8 is a sectional view through Fig. 7 approximately on the line 8-8.

Referring to the accompanying drawing by numerals, 1 indicates the body of the garment which may be provided with sleeves 2, leg mem-
bers 3 and a drop seat 4. The upper edge 5 of the drop seat 4 is provided with a binding or belt section 6 which has extensions 7 and 8 projecting beyond the side edges of the seat 4. As-
sociated with the projecting portions 7 and 8
45 are auxiliary belt members or sections 9 and 10 which are tubular. The portions 7 and 8 tele-
scopically fit into the respective members 9 and 10 as shown particularly in Fig. 5. The full
length of the extension 7 fits into member 9 and
50 has the end 11 secured by stitching 12 to the
member 9 approximately midway of the length
of member 9. Extensions 8 and 10 are arranged
in the same way.

It will be observed that the surface or portion
55 13 which contacts the body 1 is secured to the

body 1 while the outer portion 14 is left free. This is shown particularly in Figs. 5 and 6. It will be noted from Fig. 5 that the stitching 15 is arranged on opposite sides of member 9 and therefore leaves a full opening for extension 7 to slide in and out as may be desired.

When it is desired to drop the seat 4 downwardly it is merely pushed downwardly in any way and the sections 7 and 8 will slide out of the members 9 and 10 which will naturally 10 pucker more or less at points 16 and 17. The parts are of relatively proper length to permit the seat 4 to move down to a desired point. When it is desired to raise the seat 4 back to its normal upper position it is only necessary to pull on 15 the outer ends of the members 9 and 10 and by reason of the threads 12 sections 7 and 8 will be drawn into the members 9 and 10 and the seat raised. The auxiliary belt or members 9 and 10 may be then brought around to the front 20 and tied or secured by buttons, snap fasteners, or other means so that there will be presented a belt formation for the pajamas as well as means for supporting the drop seat without the use of buttons. While the extensions 7 and 8 are pre- 25 ferably formed of non-elastic textile fabric, it is evident that these members could be made of elastic without departing from the invention.

In Figs. 7 and 8 a slightly modified form of the invention is shown wherein the member 9' is used which is a single strip of material secured at 15' to the pajama body 1 whereby there will be presented an opening 18 through which the section 7 may extend. In this form of the invention the stitchings 12 are used in a similar 30 manner to that shown in Fig. 5. The sliding or telescoping action is the same in this form of the invention, except that the section 7 is not completely enclosed.

I claim:

1. A drop seat pajama comprising a body formed with sleeves, a pair of leg receiving mem-
bers and a seat portion, said seat portion being
separated from the remaining part of the body
at the waistline, said separation extending along
45 the back of the garment at the waist from one
side to the other, a belt member secured to said
seat portion along its upper edge and extending
beyond the side edges thereof, a tubular belt
member at each side of the garment secured to
50 said body a short distance above the waistline,
that part of the first belt member extending be-
yond the side edges of said seat portion tele-
scoping into said tubular belt member, and
means for securing the respective ends of the 55

first mentioned belt member to said tubular belt members intermediate the ends thereof.

2. A garment having a drop seat including a belt secured to said drop seat along its upper edge, said belt having extending portions projecting beyond said drop seat, a tubular belt telescoping over each of said extending portions, stitching for securing the ends of said extending portions to said tubular belts, and stitching for securing one end of each of said tubular belts to said garment at the sides at points above said drop seat.

3. A pajama having a drop seat, a belt stitched to the upper end edge of said drop seat, said belt having portions extending beyond the respective sides of said drop seat, a tubular belt at each side of said pajama stitched to the pajama, said extending portions of the first mentioned belt telescoping into said tubular belts for approximately one-half the length of the respective tubular belts, and stitching for securing the ends of said extending portions to said tubular belts at points approximately midway of the length of the tubular belts.

25 4. A pajama having a body provided with a

drop seat, a belt having the central part stitched to the upper end edge of said drop seat, a tubular belt on each side of said body, stitching for connecting to said body the parts of said tubular belts which contact with said body, the end portions of the first mentioned belt extending into said tubular belts for their full lengths, and means connecting the ends of said end portions to said tubular belts at points on said tubular belts spaced from said drop seat equal to the respective lengths of said end portions.

5. A pajama having a body formed with a drop seat, a belt having the central part stitched to the top end edge of said drop seat and with the remaining part projecting beyond the side edges of the drop seat, an auxiliary belt on each side of said body having one end stitched to said body so as to present a looped portion, said projecting parts of the first mentioned belt extending through said looped portions, and means for securing the ends of said projecting parts to the respective auxiliary belts at points spaced from said drop seat equal to the respective lengths of said projecting parts.

JACK BERNSTEIN.
